(57) **CLAIM**

The ornamental design for a puppy incubator as shown and described.

DESCRIPTION

FIG. 1 is a front, left and top perspective view of a puppy incubator, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is a front, left and top perspective view of the puppy incubator of FIG. 1 shown in another configuration of use; and,

FIG. 11 is a front, right and bottom perspective view of the puppy incubator of FIG. 10.

The dashed broken lines depict portions of the puppy incubator that form no part of the claimed design. The dot-dash broken lines in FIGS. 1 and 9 depict the boundaries of the enlarged views and form no part of the claimed design.
